US0D1002895S

(12) **United States Design Patent** (10) **Patent No.:** **US D1,002,895 S**
(45) **Date of Patent:** **** Oct. 24, 2023**

(54) **LIGHT**

(71) Applicant: **Ningbo Lief Energy Co., Ltd.**, Yuyao (CN)

(72) Inventor: **Qunli Feng**, Yuyao (CN)

(73) Assignee: **Ningbo Lief Energy Co., Ltd.**, Yuyao (CN)

(**) Term: **15 Years**

(21) Appl. No.: **29/834,935**

(22) Filed: **Apr. 14, 2022**

(30) **Foreign Application Priority Data**

Mar. 30, 2022 (CN) 202230174374.0

(51) **LOC (14) Cl.** **25-03**

(52) **U.S. Cl.**

USPC **D26/67**

(58) **Field of Classification Search**

(57) **CLAIM**

The ornamental design for a light, as shown and described.

DESCRIPTION

FIG. 1 is a front perspective view of a light, showing my new design;

FIG. 2 is a front view thereof;

FIG. 3 is a rear view thereof;

FIG. 4 is a right side view thereof;

FIG. 5 is a left side view thereof;

FIG. 6 is a bottom view thereof; and,

FIG. 7 is a top view thereof.

The broken lines in the drawings illustrate the portions of the light, which form no part of the claimed design.
